UNITED STATES PATENT OFFICE.

ALBERT H. EMERY, OF STAMFORD, CONNECTICUT.

PROCESS OF CONSTRUCTING AND ASSEMBLING THE PARTS OF HEAVY ORDNANCE.

SPECIFICATION forming part of Letters Patent No. 727,768, dated May 12, 1903.

Application filed May 29, 1901, Serial No. 62,388. (No model.)

To all whom it may concern:

Be it known that I, ALBERT H. EMERY, a citizen of the United States, residing at Stamford, in the county of Fairfield and State of Connecticut, have invented certain new and useful Improvements in Processes of Constructing and Assembling the Parts of Heavy Ordnance, of which the following is a specification.

The nature of my invention relates to the construction and assembling of heavy ordnance, more especially to that class in which the parts of the gun are assembled and strained from the interior outward under the process which I have described in application Serial No. 657,263, filed November 2, 1897, and in another application, Serial No. 11,904, filed April 6, 1900. Some additional details of the process are here described and claimed, and certain machinery and apparatus desirable to use in carrying out this process of construction are also described herein, which will be claimed in a divisional application.

In the accompanying drawings, Figure I shows a side elevation of a gun constructed under the process employed and herein described, one-half of the gun being in section. Figs. II and III show sections of parts of the gun on a larger scale with some modifications of the parts shown in Fig. I. Fig. IV shows a portion of a lining-tube, with the details of construction on a larger scale. Fig. V shows a general plan of a machine applicable for use in the construction and assembling of ordnance. Fig. VI shows one end of this machine in plan drawn on a larger scale. Fig. VII is an end elevation of Fig. VI, the rods 14 and 15 being shown in section. Fig. VIII shows a plan of one-half of one of the presses of this machine in section and a portion of one of the ways of the machine. Fig. IX shows a section of a packing of the piston of the press on a larger scale. Fig. X shows a section of the packing for the piston-rod of the press and a portion in section of the parts containing the packing also on a larger scale. Fig. XI shows a plan of a machine and a portion of a gun supported therein and being operated upon, together with parts of the apparatus used in the construction, one-half of the parts of the gun and apparatus being shown in section. Fig. XII shows on an en-

larged scale a section of one end of a gun member and a portion of the straining-bar, the supporting-ring, and the packings used at this point to contain the liquid. Fig. XIII shows in section similar details at the other end of the bar. Fig. XIV shows a plan of several gun members, with the straining-bar and other parts of the apparatus one-half in section arranged as in operating the parts. Fig. XV shows the section on a larger scale of a portion of the straining-bar at a point where the diameter changes, with the packings and the ducts which carry the pressure liquid. Fig. XVI shows a section of a portion of a gun at the breech end, with the method of assembling and straining the ring to position which fixes the breech-sleeve firmly in its place, with a portion of the apparatus used to strain it to position.

The gun shown in Fig. I consists of a main barrel 1, jacket 2, and hooping-tube 3 and a member 4, introduced between 1 and 2. The rear part of the bore has a lining-tube 5. The chamber is closed with a breech-block 6, which has an interrupted screw-thread seating in the breech-block 7. The gun when in use will be supported in its carriage by saddle-rings 8 and 9. The members 1 and 4 are strengthened by banding rings or hoops 10 and 11.

In Fig. II, where the breech of the gun is shown on an enlarged scale, the banding-hoop 3, instead of being made in one piece, as shown in Fig. I, consists of a main tube banded with two series of hoops or rings 3^a and 3^b. In the same figure and in Fig. III the member 4, which is shown in one piece in Fig. I interposed between the parts 1 and 2, is shown made up of three series of rings 4^a, 4^b, and 4^c. This method of making members 3 and 4 compound is especially desirable in case of very heavy guns, or those in which the pressures put upon the gases in firing are very large.

In case the member 4 is not very thick it can be made very well by forging hollow in one piece and oil-tempering, then boring and turning, ready for assembling; but in the case of very large guns, especially if high pressures are to be used in the bore and chamber, I prefer to make this member compound, as shown in Figs. II and III. The small rings

there shown can be forged and rolled to make the fibers tangential, and the parts may be finished and tempered with a much higher strength and higher limit of elasticity than can be done when forged in one piece, as shown in Fig. I. When the member 3, Fig. I, is made compound, as shown in Fig. II, the two or more series of rings 3^a 3^b should be put together with such dimensions that when assembled the outer rings will give compression to the inner, thus assembling two series of these rings by themselves. The outer rings should have tension and the inner compression, due to the relative diameters of these rings before assembling. These rings may be assembled by heating the outer ones and shrinking them onto the interior rings, or they may be pressed together mechanically without trouble by the use of suitable appliances. In the construction of this gun the tube 3 should be forged hollow and oil-tempered and annealed to such extent as may be found desirable and then turned and bored with diameters smaller than those it is to have in the finished gun. It is then strained most conveniently by hydraulic pressure acting from the interior outward to stretch these parts tangentially, forcing the interior outward toward the exterior and permanently enlarging the interior parts by this internal pressure put upon it by the liquid or fluid used in straining it. This strain used in expanding this part may be sufficient to give permanent set to the interior only, but unless the steel is very high it is best to continue the strain until the intensity is such that the piece is enlarged sufficiently to give a high strain of tension to the exterior, as well as the interior of the piece, the strain being sufficient to give a material permanent set to the exterior and a larger one to the interior. When the pressure is removed, the piece contracts. The strains of tension on the exterior will give a strain of compression to the interior parts of the tube. Both the ultimate strength and limit of elasticity are very materially increased in straining the parts this way. If this piece is compound, as shown in Fig. II, the rings 3^a 3^b are finished and assembled as previously mentioned, as is also the saddle-ring 8. This saddle-ring and the interior banding-ring 3^a are finished with interior diameters considerably larger than the exterior of member 3. They are slipped loosely over the member 3, then are put with it into the straining-machine and expanded by interior pressure, which is first sufficient to cause the external diameter of the part 3 to be enlarged until it is seized by the rings 3^a . Then the pressure is further increased until the member 3 is enlarged tangentially enough to give a high strain of tension to the rings 3^a 3^b , &c. This strain should be carried up to nearly the limit of elasticity of the rings 3^a . On removing the pressure from the interior of tube 3 it will be found that the rings 3^a 3^b are still under high tension, while the mem-

ber 3 will as a whole be under the strain of compression, due to the remaining strain of tension in 3^a 3^b , &c. The saddle-ring 8 will also be found to be securely fixed on the tube 3. The enlarging of this tube by this method of expansion increases its diameter, but decreases its length. This causes the rings 3^a 3^b , &c., not only to firmly seize it, but they are brought tightly together, their adjoining faces being pressed close to each other by the contraction longitudinally of the member 3. While the member 3 is under compression from the tension in the outer rings, if a section of this member is removed it will be found that the exterior will be under tension and the interior under compression the same in kind as when strained without the rings, these strains resulting from the interior of the tube having received a higher proportional permanent set in the process of straining than does the exterior. These relative strains are in the best direction to adapt the parts best for use in the finished gun.

The member 2, which forms the main jacket of the gun, is best made in one continuous piece, forged hollow, of strong ductile steel, then oil-tempered and, if necessary, annealed to give it sufficient ductility for further use. This piece, like most other parts of the gun, is preferably made of fluid-compressed steel. After it has been tempered and annealed, if necessary, it is bored and turned with diameters considerably smaller than it is to have in the finished gun. It is now ready to be expanded by internal pressure. It is slipped loosely into the member 3, with the saddle-rings 8 and 9 in position, and the parts are then placed in the straining-machine, as shown in Fig. XI.

The straining-machine adapted for constructing and assembling these guns is illustrated in Figs. V to X, inclusive, its use being further shown in Figs. XI to XVI, inclusive.

12 and 13 are two hydraulic presses connected with each other by ways 14 and 15, the latter being held in position by supports 16.

17 and 18 are beams provided to move along the ways 14 15 to support and fix the work in position. When adjusted to convenient points, they are secured to the ways at such points by pins or bolts 19.

The presses 12 and 13 may be supported in any suitable way to render them convenient for use. One or both of these presses should be movable. They are fixed to the ways at any convenient points by pins or bolts 19. The presses 12 13 and beams 17 and 18 are made to fit the ways, as shown in Fig. VII, but have openings at the end of the cross-heads and beams which allow them to freely pass the supports 16. The ways 14 and 15, if long, are best made in two or more pieces, united by a screw splicing-piece 20. (Shown in Fig. VIII.)

The presses 12 and 13 may be constructed as shown in Fig. VIII, where 12^a represents

the cross-head of the press 12 and consists of a large beam, into which the cylinder 12^b is screwed. The outer end of this cylinder is closed by the head 21, which is secured to the 5 cylinder 12^b by stud-bolts 22 and nuts 23. The piston 24 is packed by packings 25 to receive pressure in either direction. The piston-rod 26 is threaded at its outer end for the ready adjustment with the parts used in connection therewith. This adjustment is more 10 readily performed in many cases by having a smaller part 27 extending therefrom, which is also threaded. The packing 25 is shown in detail on a large scale in Fig. IX. It consists 15 of a ring 28, having a thin lip 28^a which closes to prevent the passage of the fluid, being closed naturally by the action of the fluid and aided and assisted in its closing by the elastic packing 29, which is usually made of 20 leather.

30 represents screws which force the ring 31 against the packing 29 and crowd the latter against the ring 28 in the cylindrical wall of the press. That this may be more readily 25 accomplished a fibrous elastic packing 32 is placed between the ring 31 and the packing 29. The cupped ring 28 is provided with a series of grooves, which makes its bearing-faces on the piston 24 and the wall of the 30 cylinder 12^b less in area than that of the liquid-bearing surface on the opposite faces and causes it to seal the joint better than when these grooves are not used. The cross-head 12^a of the press is provided with a lining 33. (Shown in Figs. VIII and X.) This lining may, if desired, overlap the joint between 12^a and 12^b, as shown in Fig. VIII. It has a lip or flange 33^a extending into the cross-head around the piston-rod and contains 35 in a recess between it and the piston-rod a packing 34. (Shown on an enlarged scale in Fig. X.)

35 shows a metal ring best made of aluminum-bronze or other bronze, with two lips on 40 its rear surface, one closing the joint between it and the piston-rod and the other closing the joint between it and the flange 33^a of lining 33. To reduce the bearing-surface on the working faces of these lips, small grooves are 45 provided, and to insure a more thorough sealing an elastic cup-packing ring 36 is provided. The latter is forced out against the lips of the ring 35 by the metal ring 37, the whole packing being securely pressed together and held in position by the screw-collar 38.

In Fig. XI the members 2 and 3 of the gun are shown in position in the machine in the process of straining them, as previously mentioned. They should have after straining 50 both interior and exterior diameters smaller than they are to have in the finished gun. The member 3 may be strained by itself without 55 2, as described, or it may be put into the machine with 2 before either of them has been strained, the two parts being slipped loosely together, with the saddle-rings 8 and

9 in position, as shown. These latter should be finished or nearly finished before assembling and should have such internal diameters relatively to the members 2 and 3 that they will not be enlarged in the process of straining the latter to a greater extent than is desired. In straining the parts 2 and 3 together the part 2 is slipped over the straining-bar 39 and rests in rings 40 and 41, the latter resting in the beams 17 and 18. 17 is fixed to the ways by bolts 19, while 18 is free to move as the work progresses. The liquid used to force the parts out is put into the 80 pump-chamber in the bar 39 and is forced by the plunger 42 out through the duct 43 into the annular space between the straining-bar and gun member 2. This liquid is confined in this chamber by packings 44 and 45. (Shown in Fig. XI and on an enlarged scale in Figs. XII and XIII.) The packing 44 may be a single ring, as shown in Figs. XII and XIII, or it may be a compound packing, if preferred. When made in a single ring, it 85 should be of steel or hard bronze and seated in the ring 40 or 41, or it may, if preferred, be seated in the gun member, as shown in Fig. XIII. The surface against which this packing rests and slides as the member is expanded may be polished to prevent abrasion and tearing of the packing. When this packing is used, as shown in Fig. XII, the end of the gun member 2 may be polished to prevent abrasion as the member stretches outward and slides on the packings. The packing 44, if made in one piece, had best be grooved, as shown, to reduce its bearing-surfaces. In Fig. XII the packing 45, which is used to prevent the liquid from flowing away 90 around the straining-bar, is placed further outward than the packing 44, while in Fig. XIII the packing 45, which prevents the flow of the liquid past the left-hand end of the straining-bar, is shown farther inward than 95 the position of the packing 44, and when 45 is so located 44 may be dispensed with, the gun member 2 resting directly against the supporting-ring 41. The member 2 may be centered in the rings 40 and 41 either by 100 screws 46 (shown in Fig. XIII) or by the member fitting the rings 40 and 41 for a portion of its length, as shown in Fig. XII. When made as here shown, as the member 2 enlarges the little supporting and centering corner where it bears on the rings 40 is 105 crushed away to the extent necessary to allow the desired expansion of the part 2. The plunger 42 is suitably packed by a packing 47, similar to the packings 45. (Shown in 110 Figs. XII and XIII.) These packings each consist of a screw-collar 48, best made of hard bronze and provided at their inner ends with a conical lip 49, which seals the joint between it and the part in which it is screwed. To 115 make this sealing more perfect, grooves are provided in the exterior of this lip, which reduce its bearing-surface and aid in sealing. The sleeve 48 has a recess made by the ex- 120 125 130

tending lip 49 and contains the packing, which consists of a coned ring 50, flexible packing 51, and adjusting-ring 52, which forces a fibrous packing 53 against the flexible packing 51, crowding the latter against a thin lip 54, which extends back from the rear of the coned ring 50. The working faces of the ring 50 are provided with a series of grooves to reduce the bearing-surface and increase the pressure per unit of area on the remaining parts of these surfaces. This ring is best made of hard hammered bronze; but it may be made of steel. The elastic packing 51 may be made of leather. Fine hemp cords 15 are a good material with which to make 53, and bronze is suitable for the ring 52, which is preferably grooved on its outer bearing-faces, as shown in the drawings. The plunger 42 is forced against the liquid in the straining-bar 39 by any suitable means; but as shown in Fig. XI it is forced forward by the piston-rod 26 of the press 12, to which it is connected by the screw-sleeve 54. On the piston-rod 26 of the press 13 is screwed a collar 25 55, with a projecting flange resting against the ring 40 and forcing it against the gun member 2 with sufficient pressure to close the joints at the packings 44 and keep them closed during the process of straining. This 30 pressure will have to first overcome that put upon the plunger 42 and, second, apply enough additional pressure to keep the packings 44 closed. In the process of straining these parts as they extend tangentially they contract longitudinally, the piston-rod 26 following up this contraction and keeping the parts together, as specified.

In the case illustrated the first parts of the members 3 and 2 are thinner than are the 40 other parts thereof and are not, therefore, able to bear the pressure required to properly strain the thicker parts of these pieces. For this reason limiting-bands 56 and 57 are slipped loosely over these parts. They are 45 expanded until the portion contained in these bands fills by expanding the limiting-bands, and the other part is afterward farther extended by the increased pressure then applied to the fluid in or around the straining-bar. 50 When the parts 2 and 3 are sufficiently expanded, the pressure on the liquid is removed by any convenient means, but usually by withdrawing the plunger 42. The removal of this pressure allows the parts 2 and 3 to 55 contract the part 3 then tightly banding the member 2, the latter having been extended more in proportion to its diameter than has the former. It will also be found, whether the part 3 was strained previously to its being assembled with the part 2 or not, that both the parts 2 and 3 would, if separated, be found to have tension on their exteriors and compression on the interior parts thereof. The contraction of the parts 2 and 3 on the 60 removal of the liquid-pressure will not usually be sufficient to free them from the limiting-bands 56 and 57. These bands may be

pressed off by any suitable means. A good way is to force liquid between their inner surfaces and the outer surface of the part they 70 inclose through ducts 56-57, when their conical form immediately causes their release, they slipping back from the interior pieces as soon as the liquid is forced between them with sufficient pressure to separate the adjoining 75 surfaces. If the metal in the tube 3 is very hard, it need not be expanded before the member 2 is inserted, and in even other cases it may be sufficiently expanded by expanding it and the member 2 together in one operation, as described; but in this case the inner part 2 will always receive a larger permanent set while being expanded than will the part 3. Members 2, 3, and 4 may be loosely assembled and expanded together, or members 2, 80 3, and 4 and 1 may be loosely assembled and all expanded at one operation; but it will usually be preferable to assemble parts 2 and 3 together and expand 2 into 3, as described, and afterward assemble with them parts 1 85 and 4 and expand them until the parts 2 and 3 are properly extended or until when the pressure is removed from the interior parts and they are allowed to contract the remaining strains of tension on the exterior parts 90 are as great as is desired.

If the member 4 is made in one tube of one thickness of metal, it will be better to expand it into the assembled pieces 2 and 3 before inserting the barrel 1, which is done by 100 using the apparatus in a similar way to that shown for assembling and straining parts 2 and 3. If the member 4 is compound and made up of two or more series of rings or hoops, as shown in Figs. II and III, with 105 higher elastic limits than the parts 1 and 2, these rings are preferably pressed together with slight strains of tension on the exterior and compression on the interior rings, owing to the relative diameters given to their adjoining faces when they are dressed. After they are assembled with each other they are slipped loosely into the member 2, the outer rings having a diameter smaller than the corresponding diameter of the receiving member 110 2, so that these rings when strained out to position in the finished gun will have a greater strain of tension than will the adjoining inner surface of the member 2, which has a lower elastic limit. The member 4, whether 115 simple or compound, is strained out to position by the method illustrated in Fig. XIV, where the straining-bar 39 is shown extending through the whole length of the gun, with the parts 1, 2, 3, and 4 in position around it, 120 ready for the operation of straining. In this case the bar is supported at the muzzle end by the sleeve 59, which is screwed to the piston-rod 26 of the press 13. The other end is supported in the machine by the beam 17 and 125 ring or collar 41, which parts are shown in Fig. XI, but not in Fig. XIV. The barrel 1 is slipped loosely into the member 4 and provided at its front end with a limiting-band 130 60

to prevent its being strained too greatly at that part. The straining-bar 39 and ring 59 are provided with packings 44 and 45, similar to those described, and illustrated in Figs. XII and XIII. In the case illustrated the left-hand end of the straining-bar is much larger than the right-hand end, owing to the offset at the front of the breech-sleeve 7 and the offset in the gun-barrel at the point where the lining-tube 5 terminates. Owing to these offsets were no packings provided therewith when a heavy pressure is put upon the liquid there would be a large longitudinal thrust, tending to carry the straining-bar to the left and the parts of the gun to the right. This thrust in the case of heavy guns would be so extreme as to be difficult to manage, for which reason packings are provided to prevent the liquid from acting on these annular areas around the bar. A pair of these packings are placed at 61 and another pair at the offset at 62, the latter being illustrated and shown on the larger scale at Fig. XV, where packing 63^a is precisely similar and acts in the same way as those already described; but packing 63 is of somewhat different construction, owing to its being necessary to insert it in a groove in the solid bar. When this packing is used in the form shown in Fig. XIII, the parts 50, 51, 52, 30 and 53 are readily assembled; but when they are set in a recess in the solid bar, as shown in Fig. XV, the assembling is different. In this case the parts 50, 51, 52, and 53 are first put into the groove by slipping them over the bar till they are over the groove and then compressing them to position, the part 52 being then forced firmly against the others and a cut ring 64 inserted to keep them tightly together. In slipping the bar 39 into position the packing 40 63 is liable to be injured and distorted unless precautions are taken to prevent it. A simple and good way to avoid injury is to slip a ring 65^b, which fits the bar 39, immediately over the center of the packing 63. When the bar is slipped to its place, the ring 65^b strikes against the shoulder and the barrel 1 and is slipped off the packing, which readily passes without disturbance into the surrounding part of the barrel. When the parts are in position 50 ready to begin the straining, plunger 42 is forced by the press 12 or other suitable means against the liquid in the straining-bar 39, forcing it out through ducts 43, 65, and 66 into the annular spaces around the bar between it and the surrounding members of the gun, expanding the barrel 1 and the screw-sleeve 7 out against the exterior parts and permanently enlarging their diameters sufficient to give the desired strain of tension to the exterior parts of the gun and permanent compression to the members 1 and 4 after the removal of the liquid-pressure. Should there be leakage from the annular space around the straining-bar sufficient to force liquid between the packings 63, 63^a, it will be carried away with slight pressure through the duct 66^a, (shown in Figs. XIV and XV,) leading into outlet 67, (shown in Fig. XIV,) or any other outlet which may preferably be provided. A similar duct 68 (shown in dotted lines in Fig. XIV) will carry away the liquid which may leak past the packings at 61 and avoid longitudinal thrust at that point. In straining the barrel 1 and sleeve 7 to position the work may be done simultaneously, as described, 75 liquid of the same pressure being forced into the interior of all these parts, or I may provide liquid of different pressures for the different parts of the bore and sleeve and still strain them all at one operation. Another 80 method which may be advisably practiced in some cases would be to strain the sleeve 7 to position either before or after straining the barrel 1, this piece being strained first one part of its length to position and subsequently 85 the other part, or pressure may be put upon part of the barrel, straining it partially in one part and fully in another and subsequent additional straining complete the straining of the part which was insufficiently strained at 90 first. If the member 4 is compound, it and 1 will be assembled together and slipped loosely into the part 2 and then the whole expanded until the diameter of the part 1 has been increased sufficiently to give the desired 95 tension to all the parts exterior thereto, the diameters of the rings next to the member 2 having been previously made of such sizes relatively to the adjoining surfaces of the part 2 that they will have in the finished gun a 100 much higher tensile strain than will the interior of the part 2. Enlarging the diameter of the barrel 1 shortens it longitudinally and will give at one stage of the process a longitudinal strain of tension owing to this shortening, and the pressure of the liquid should be increased until the interior of this barrel receives a strain of compression sufficient to give longitudinal as well as tangential compression. When the pressure of the liquid 105 is removed and the parts are allowed to contract, it will be found that the barrel 1 will be under a heavy tangential strain of compression, and the member 4 may in part or whole also be under a strain of compression by reason of the tangential strain of tension on the parts exterior thereto. The front part of the barrel will have a strain of tension on its exterior and compression on the interior as desired. In all cases if the member 4 is compounded of rings, as shown in Figs. II and III, the construction should be such as to give a strain of tension on the exterior rings next to the part 2 greater than the tension on that member when firing with the maximum 110 charges. In the normal state before firing while the members 2 and 3 are under tension as a whole, giving compression to the inner parts as a whole, the interior of the member 2 may be under a strain of compression. 115

It will sometimes happen that the screw-sleeve 7 is assembled after the parts 1 and 4 have been strained to position. It will also sometimes happen, even when the screw- 120

125

130

sleeve 7 has been simultaneously or previously strained to position, that in straining 1 and 4 to position the pressure is not sufficient to give the desired longitudinal compression in the barrel 1. In this case and in some others it is desirable to insert a ring 69 between the breech-sleeve 7 and the barrel 1, as shown in Fig. II, or breech-sleeve 7 and members 1 and 4, as shown in Fig. XVI, this 10 ring 69 being strained to position after the straining of screw-sleeve 7 and members 1 and 4. It may be strained out by radial liquid-pressure put upon its exterior surface, or it may be strained out to position by the method 15 shown in Fig. XVI, where the interior is bored conical and the coned piece 70 is forced into it by heavy pressure, expanding it until it fits tightly against the member 2 and until the compression is sufficient to give a longitudinal 20 thrust against the breech-sleeve 7 and the member 1 or 1 and 4 approaching to or greater than the thrust which will come upon the breech-block when the gun is fired. In the latter case the pressure upon the outer 25 screw-threads of the breech-sleeve 7 is not increased by firing the gun, and all backlash of this piece is avoided. This sleeve is not threaded on its interior to receive the breech-block usually until after the complete expansion 30 of the ring 69. After the breech-sleeve 7, members 1 and 4, and the ring 69 have been expanded to place the gun may be bored, the front part ready for rifling and the rear part ready to receive the lining 5, which is to be 35 inserted therein. The chamber may also be finished and the sleeve 7 threaded on its interior and the exterior of the gun finished with proper dimensions. The lining-tube 5 is then inserted. I prefer usually to rifle all 40 that part of the bore down to the lining and to finish the lining on its exterior and interior mainly and rifle it; making it of such diameter that when inserted its inner diameter will be that desired in the finished gun. 45 If preferred, the rifling of the gun and this lining-tube or the final boring and rifling of the gun and this lining-tube can be left until the tube has been seated in position; but the process of rifling them first is convenient 50 when considered from the point of conveniently relining the gun, especially when this work is done on shipboard or in the defenses where the gun is in use.

The method of inserting the lining I have 55 fully described in another application filed April 6, 1900, Serial No. 11,904. It consists, briefly, in forcing a film of fluid between the lining and the surrounding parts under a sufficient pressure to insure compression of 60 the lining enough to allow it to be removed forward to its proper seat in the gun, when the pressure on the liquid is removed and the liquid is allowed to flow out through a duct 71. (Shown in Figs. II and IV.) This lining 65 5 is made of hard highly-elastic thoroughly-worked oil-tempered steel, and should be finished with such dimensions that when assem-

bled in its proper position in the gun it will be under a high strain of compression, preferably so high that when the walls of the gun 70 are expanded in firing the compression on this piece will not be wholly removed, in which case there is no danger of its splitting, and it more readily bears the severe strains put upon the lands by the packing of the projectile during the act of firing. For the more ready insertion of this lining-tube it is usually prepared with one or more offsets or changes of diameter, as illustrated in the case shown, where there are three, one at 72, one at 73, 80 and one at 74, the diameters of this lining before insertion being less than that of the chamber, but larger than that of its corresponding seats in the barrel 1. It is readily slipped into the chamber and barrel, but 85 stops when it reaches within one offset or space of its final resting-place. The liquid-pressure is then introduced to reduce its diameter, so that it can be forced forward to its seat. To retain this pressure, a packing 90 75, entirely similar to the packing 45, already described, is provided and applied to the lining at the front end of such lining-tube, as shown in Fig. IV. A packing is also provided around the head of the assembling-tool 95 to retain the liquid at the rear end of the tube, so that pressure will be applied throughout the whole length of the lining-tube to reduce its diameter as desired. The liquid is forced into the annular space between the 100 lining-tube and the barrel 1 through the duct 71 until the pressure is sufficient to give the required reduction to the lining 5. As this tube is moved forward some of the liquid around the tube may leak out through the 105 packings, the balance flowing back through the duct 71, and when the piece is finally seated any liquid remaining between the parts will flow out as soon as the pressure is removed, owing to the expansion of the lining-tube or the expansion of the lining-tube and the contraction of the walls around it. The front part of the tube 5 has a thin lip or sleeve 76 extending beyond the packing 75, covering the joint between it and the member 1, itself making a joint tight at its front end with the part 1, the interior of the lining-tube and barrel being flush at that point. The exterior of this lip 76 is surrounded with a shallow groove 77, made in it or in the adjoining part for the purpose of reducing the surface of contact to avoid the flow of gas through this joint when the gun is fired. In Fig. IV these grooves are shown in the barrel 1 instead of on the sleeve, where they are 115 usually placed.

The rear of the tube 5 is provided with threads 78 to engage the threads of the assembling-tool when the lining is to be inserted or removed from the gun. 79 is a thin 120 overlapping piece, best made of bronze or copper, secured at its front end to the tube 5 and overlapping and closing at its rear end the joint between the assembling-tool and the 130

lining-tube 5 during the process of inserting or removing the lining-tube. It is secured to the tube by the metallic packing 83, tightly forced therein.

5 80 is a sleeve made of steel or hard bronze which screws into and fills the assembling-threads provided at the rear end of the lining 5 and has provided on its interior a seat or seats, slightly conical, into which the finish-
10 ing-piece 81 is tightly forced to expand 80 and the rear end of tube 5 to position and make a proper finish for the rear of the lining-tube. It is best made of hard bronze or highly-tempered steel and of diameters sufficient to cause it to have a heavy resultant strain of compression when forced to its seat. To avoid the flow of gas past either of these pieces, a series of grooves 82 82 are provided, as shown in Fig. IV, which by reducing the 15 surface of pressure between the adjoining faces tend to exclude the passage of the gases through these joints. Should it happen, however, that gas goes through in firing, it will pass out through the duct 71 and give notice 20 that there is leakage at that point.

25 It will sometimes happen, especially in the case of large guns, that the pressures required to properly expand the parts 1 and 4 to position after assembling are so great as to cause 30 great difficulty in handling them, in which case the parts 1 and 4 may be strained together, the parts 2 and 3 assembled and strained together by themselves, and then parts 2 and 3 as one piece and the parts 1 and 4 as another 35 piece be brought together and assembled by precisely the same process that is used to insert the lining 5. The assembling-machine described is suitable for this use. The process of assembling parts of the gun in this 40 way is more fully described and illustrated in another application filed April 6, 1900, Serial No. 11,904. In passing liquid through the duct 71 care must be taken to exclude it from the joints between the members through 45 which it passes, which may be done by the use of a piece 84, (shown in Figs. II and IV,) which has sealed joints at its outer and inner ends, both of which are made conical and tightened or closed by the action of the 50 screw 85. (Shown in Fig. II.)

Having thus described my invention, the following is what I claim as new therein and desire to secure by Letters Patent:

1. The process of expanding the interior 55 of a tube, jacket, or other part of a gun, outward against the exterior parts surrounding it, or against the exterior parts of itself, by means of liquid-pressure acting on a part or the whole of the interior of said piece, susp- 60 taining it by a limiting band or bands, and preventing the thinner parts of said piece which is being expanded from being unduly

strained or enlarged by the pressure required on the thicker parts thereof, substantially as and for the purpose described. 65

2. The process of outwardly expanding a tube, jacket, or other part of a gun, having changes or offsets in its interior diameter, which consists in introducing a straining-bar provided with corresponding offsets and suitable packings at or near the extremities of the part being strained, and at the offsets, which will retain the pressure liquid and permit the desired radial pressure, but prevent longitudinal pressure between the bar and 75 the part being strained, then introducing liquid into the chambers thus formed, under pressure, sufficient to cause the desired expansion.

3. In the construction and assembling of 80 guns, the process of assembling two or more parts thereof, which consists in constructing said parts with such relative internal and external diameters that they will fit one loosely within another, putting the loose parts together in their proper relative positions and then introducing within an inner part hydraulic or fluid pressure sufficient to force the inner part or parts out against the exterior part or parts, and permanently enlarge 85 the inner loose part or parts by expanding the metal thereof to a sufficient extent to cause the inner part or parts to be firmly seized and held in place by the outer.

4. The process of constructing and assem- 90 bling guns, which consists in providing three or more concentric members, of which an intermediate member has a higher limit of elasticity than the member which is to immediately surround it when assembled, then 95 slipping said members together, one within another, then introducing into an inner mem- 100 ber fluid-pressure sufficient to expand the inner members firmly against the outer, and leave the intermediate member under a per- 105 manent strain of tension superior to that in the inner part of the member immediately surrounding it.

5. In constructing heavy guns, the process 110 of assembling, which consists in inserting one or more lining-tubes, a breech-sleeve and a ring interposed between the lining and breech-sleeve, expanding the lining into position, suitably securing the breech-sleeve and subsequently expanding the interposed 115 ring so as to apply longitudinal compression to the lining and breech-sleeve, as explained.

The foregoing specification signed this 20th day of May, 1901.

ALBERT H. EMERY.
